MOUNTING FOR WALL FORMS

Ubaldo Fiorenzi, Sinigallia, Italy

Application August 8, 1946, Serial No. 689,129
In Italy September 8, 1945

12 Claims. (Cl. 25—131)

1 Subject of the present invention is a mounting for wall forms by means of which it is possible to cast simultaneously and with the highest desirable precision all inner and outer walls of a building, at the same time obtaining the openings for the doors and windows, as well as the ducts for the layout of conduits and cables for the home and office appliances.

The mounting comprises a double frame for the panels destined to constitute the wall form sides for casting the concrete. Suitably designed devices and clamps or joints allow to adapt the mounting to the characteristic of the building and to the plan of the rooms under construction, as well as to conform the dimensions of the wall form to those of the walls to be built.

The proposed mounting, therefore, may be used for the construction of buildings having any desired layout, and may successively be employed for different structures. Hence the initially small depreciation charges are readily accounted for. In fact, as soon as the casting operation has been performed to a desired height of the wall, corresponding to that of the wall form, the panels already used are stripped by a quick and simple operation and lifted to constitute the new wall form, limiting the upper portion of the same wall.

The proposed mounting is preferably made of metal such as light-weight, tough metals in order to reduce the weight of the assembly and have parts that can be easily manipulated.

Some particular joining devices or sleeves allow to lock the panels forming the walls of the form at different heights while the wall is built.

It is to be noted that the supporting structure is also utilized for anchoring the scaffolds which are fastened on the supporting frame by means of suitably mounted brackets which may be lifted as the building of the wall progresses.

The appended drawings show one embodiment of the invention in which:

Fig. 1 is an elevation of the mounting for the construction of a portion of a vertical wall comprising the opening for a door. In said figure is visible the supporting frame carrying the panels of the form limiting the outside surface of the wall;

Fig. 2 is a horizontal section of the wall and of the base of the supporting frame near to the ground, immediately after the beginning of the casting of the wall;

Fig. 3 is a vertical section of the wall under construction as well as the casting form and the corresponding panel-supporting frame, during the

2 preparing of the form, and the assembling of the corresponding panels;

Fig. 4 is a transverse section, at a larger scale, of the wall under construction, as well as of the mounting for the casting form;

Fig. 5 is a horizontal section on line A—A of Fig. 4;

Figs. 6 and 7 are a front view and section, respectively, of the joints between the panels constituting the form;

Fig. 8 represents the side of the panels connected by the splicing strip;

Fig. 9 is a plan view of the sleeve used to lock the panels in position, when the wall rises;

Fig. 10 is a top view of the sleeve of Fig. 9; and Fig. 11 is a top view of one section of the sleeve illustrated in Figs. 9 and 10.

The proposed assembly comprises a supporting frame constituted by uprights 1, 1' preferably having a circular section arranged in a double row on each side, respectively, of the space of the wall to be erected, which space is to be limited by the wall form. The uprights are anchored to the ground in a particular way. The inner row

25 1 is mounted on a base 2 constituted by a sill having an angular cross-section and placed on the ground so as to flank the walls to be erected. On base 2, at equal distances, are distributed holes 3 utilized as seats of cleats apt to anchor base 2 to the ground. These sills forming base 2 may be of different lengths and are joined longitudinally by links made of plates and bolts, while right-angle joints are obtained by means of clamps.

30 35 On base 2 are fixed a first set of seats forming supports or angle pieces 4 for supporting uprights 1, at a predetermined distance, dependent on the dimensions of the walls to be built, on those of the resistant section of the assembly, and further, on the stresses which it has to stand.

Numeral 5 indicates a second set of seats forming supports for the outer uprights 1'.

The internal uprights 1 and the external uprights 1' are transversely stiffened by spreaders 6 and longitudinally by reinforcing ties 7. The rigid connection of said structure is obtained by means of particular coupling clamps (which shall be discussed in detail later on) and which allow to lock the uprights and cross members 6 and 7 in a predetermined arrangement and to ensure the stability of the structure, while it is simple to strip the parts in order to use the supporting frame for another structure.

The coupling members connecting uprights 1 and 1' with cross members 6 are indicated by 8,

while 9 indicates the coupling members between the transverse cross members 6 and longitudinal cross members 7.

The panels constituting the form for the casting are designated by 10; they are supported by means of pairs of opposite brackets 11-12, which are fastened to the uprights by sleeves 13.

These sleeves 13 comprise two holding means (Figs. 4, 9, 10 and 11) 13', 13''; the holding means 13' is constituted by a saddle shaped as a hollow semi-cylinder, fitting onto the section of upright 1 which it engages; the outside shape of 13' can be seen in Fig. 4, while its section can be seen from the detail in Fig. 10; the holding means 13'' is shaped as a hollow semi-cylinder provided with two lateral wings 14 having two slots for the shanks of two screws 15, which when parts 13' and 13'' are assembled by these screws engage threads in holding means 13'.

The connection between brackets 11-12 and sleeves 13 is so that the brackets are adjustable in length in order to adapt the spacing between panels facing one another to the desired wall thickness.

In assembling, the two sections 13' 13'' of sleeve 13, are joined by bringing piece 13' in close contact with the upright. Screws 15 are loosened so that their shanks protrude beyond the coupling surface (Fig. 10). The section 13'' is then placed against upright 1 just above 13' and permitted to slide down till the slots in 14 engage the shanks of screws 15; thereafter screws are tightened to lock sleeve 13 to one of posts 1 or 1'. The particular shape of sleeve 13 has the advantage of allowing a quick assembly and disassembly of the parts, since screws 15 need not be completely unscrewed from their seat, but just loosened, so as to disengage section 13'' from section 13'. This is an important advantage; it also prevents the screws from getting lost which could easily happen if they were to be completely unscrewed during the stripping.

Brackets 11 and 12 extend through holes provided in piece 13'. Locking screws 16 (Fig. 4) are provided to fix the position of the brackets 11 and 12 in piece 13' to change the effective length of the brackets in order to realize the desired spacing between opposing panels 10.

Brackets 11 are constituted by a rod, bent at right angles and having a stop 17 near its end 11'. Panels 10 are made of soft steel sheets, stiffened by embossed ribs 10' and reinforced with a perimetral edge 18 with holes 19. In order to form a wall of the desired length and of constant height, a plurality of panels 10 of different lengths are assembled by bolts extending through holes 19 in edges 18 (see Figs. 6 and 7). The joint is completed by securing to the joint zone of 18, a strip 20, fastened to 18 by bolts 21.

The same holes 19 are used for supporting the panels 10 through brackets 11, 11', their upper ends protruding through holes 19 until arrested by stops 17. Panel 10 is thereby supported on bracket 11; at its lower end, bracket 12 provides the support. Its end 12' however, is bent back so as to constitute a hook which engages a hole 19 in the lower edge 18 of panel 10.

The assembly of the form proposed by this invention is as follows:

Having previously laid out on the ground the plan for the walls with the foundations already filled and the ground thoroughly leveled, the supporting frame is erected. To this effect, base 2 is laid out to correspond with the inner side of the room wall to be built and anchored to the ground along the perimeter of the wall by means

of cleats or spikes. Having then established, in accordance with the dimensions of the room, the spacing of uprights 1, angle pieces 4 are fastened to base 2 and locked in place by means of set screws 23. Angle piece 4, carrying a seat for the upright 1, has a triangular form (Fig. 5) and is fastened with its shorter side to the base 2, and with its other side to a cross-tie 24, which crosses perpendicularly the wall near the ground and connects the inner upright 1 with the outer upright 1'. Tie 24 is anchored to the ground at its outer end by a spike 25. The seat forming support 5 of upright 1' is secured to tie 24. Locking screws 5' lock 5 to the tie 24 at the desired distance from angle piece 4. Above supports 4 and 5 are provided, clamps 26 holding uprights 1 and 1' in their respective supports 4 and 5. Having thus assembled the supporting base, uprights 1 are fitted into angle pieces 4, and their lower ends held by tightening the screws on clamps 26; in the same way uprights 1' are inserted into supports 5 and locked therein.

The wall is shown by numeral 27. An opening, for instance, for a door, as indicated in Fig. 1, is secured by providing a corresponding pattern 28. To form the corner of a wall, base 2 is connected by splicing clamp 28' to an adjacent portion 2' laid out perpendicularly to the base 2. Clamps 28' assure a rigid right-angle connection of the two base portions 2 and 2' at their junction.

Having assembled uprights 1 and 1', they are counterbraced by means of cross members 6, fastened to the uprights 1 and 1' by two-section coupling members which are locked by tightening bolts 8'. Thus the coupling member 8 is clamped around the uprights remaining fixed at a desired height. One of the sections of coupling member 8 is provided with a hole for the cross members 6, and with a locking screw, a sleeve 9 can be locked to cross member 6 in any desired position by set screw 9'. Sleeve 9 carries a lateral extension in which is machined the hole for the passage of the transverse cross member 7, locked to sleeve 9 by screw 29.

Thus a sturdy metal assembly is obtained, which surrounds all the walls to be built. This cage-shaped structure is used to support and lift the form for casting the concrete as well as to carry the scaffolds. The form is assembled, as mentioned already, by mounting supports 13 on the uprights and fixing them at the desired height, engaging brackets 11 and 12 in 13, and securing panels 10 to these brackets. The sides of panels 10 constitute the form for casting. After insertion of the patterns for door and window openings, the concrete is poured.

As soon as the casting has been completed up to the height of the prearranged form, usually the next day, one can proceed to lift the panels. By loosening screws 15, holding means 13' and 13'' are disengaged; sleeve 13 is stripped off the upright with brackets 11 and 12, already disengaged from the panels. The panels 10 are lifted to the necessary height by means of pulley 30 (Fig. 3), that can be easily mounted on cross members 6 where they are fixed in the already known way by securing to the uprights the new position to which supports 13 with brackets 11 and 12 have been moved.

It is further to be noted that, as already pointed out, the supporting frame is used also to carry the scaffolds which are put in service after the first concrete belt has been cast and raised by means of a pulley and anchored to the upper

cross ties as the wall is rising in height. These scaffolds are constituted by a single board assembly 32 (Fig. 3), resting on brackets 33 fastened to posts by means of clamps provided with clamping bolts. The bracket is supported on strut 34 which is anchored at its lower end on through tie 35, on which strut 34 acts with a shearing stress. The through tie or anchoring rod 35 crosses wall 27 and is carried on posts 1 and 1' extending through holes 36 provided for this purpose. During the concrete setting, care should be taken by slightly moving the rod, that the concrete does not adhere to the sides of 35, in order that it can be easily extracted when the setting is completed.

Rod 35 is provided to firmly anchor the posts to the wall, while the wall is being built, and cross members 6 and 7 are removed and replaced at higher positions. These rods are distributed in height about one every two casting heights.

It is evident that the form, dimensions and constructive details of the present invention may vary according to necessities without exceeding the scope of the present invention.

The holes for the passage of the rods can be replaced by special sleeves, provided with lateral extensions. The extensions form the seat for rods, locked by set screws or the like.

The panels 10 can be fixed by special pieces, having two portions locked by screws and rotatable on a pivot. These portions are at different distances for clamping panels of different thickness.

I claim:

1. A mounting for wall forms comprising a base adapted to be secured to the ground; a first set of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats holding means arranged on said uprights for vertical adjustment; means combined with said holding means for rigidly fastening the same in vertically adjusted position wherever desired; and means maintained in said holding means to support a plurality of wall forms from said uprights.

2. A mounting for wall forms comprising a base adapted to be secured to the ground; a first set of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; holding means arranged on said uprights for vertical adjustment; means combined with said holding means for rigidly fastening the same in vertically adjusted position, wherever desired, and brackets maintained in said holding means and adapted for adjustment therein in a horizontal direction and adapted to support a plurality of wall forms.

3. A mounting for wall forms comprising a base adapted to be secured to the ground; a first set

of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; holding means arranged on said uprights for vertical adjustment; generally horizontal bores in said holding means; brackets passing through said horizontal bores; and means for locking said brackets in said bores in selected horizontal positions, said brackets being adapted to support a plurality of wall forms.

4. A mounting for wall forms constructed in accordance with claim 2, wherein the said holding means comprises complementary clamp sections; generally horizontally projected stop elements provided on one of said sections; vertically directed slots provided on the other clamp section whereby the latter can be moved onto said first clamp section to be held thereon by engagement of said stop elements in said slots; and means for relatively locking said two clamp sections.

5. A mounting for wall forms constructed in accordance with claim 2, wherein the said holding means comprises complementary clamp sections; locking screws disposed on one of said sections and projecting horizontally therefrom; vertically directed slots provided on the other of said clamp sections whereby the latter can be moved onto said first clamp section to be held thereon by engagement of the shanks of said screws in said slots and whereby the two clamp sections can be relatively locked by tightening said screws.

6. A mounting for wall forms constructed in accordance with claim 2, wherein the said holding means comprises complementary clamp sections; generally horizontally projected stop elements provided on one of said sections; vertically directed slots provided on the other clamp section whereby the latter can be moved onto said first clamp section to be held thereon by engagement of said stop elements in said slots; means for relatively locking said two clamp sections; generally horizontal bores in one of said clamp sections for slidably receiving said brackets; and means for locking said brackets in said horizontal bores in selected horizontal positions.

7. A mounting for wall forms comprising a substantially L-shaped sill adapted to be secured with one of its faces to the ground; a first set of seats forming supports; means to secure said supports detachably and in any desired horizontal positions to the other face of said sill; track forming cross ties provided at ground level and detachably secured with one end to said sill at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; and means to support a plurality of wall forms from said uprights.

8. A mounting for wall forms comprising a substantially L-formed sill adapted to be secured to the ground; a plurality of substantially triangular elements; seats formed on the top of said tri-

angles; track forming cross ties provided at ground level; means for detachably locking said triangles with one side to said sill at selected horizontal points; means for detachably locking one end of said cross ties to another side of said triangles; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; and means to support a plurality of wall forms from said uprights.

9. A mounting for wall forms comprising a base adapted to be secured to the ground; a first set of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; holding means arranged on said uprights for vertical adjustment; brackets having a plurality of shank forming portions disposed at a relative angle; generally horizontal bores provided in said holding means and adapted to receive one of said shank portions; and a plurality of wall forms provided with apertured marginal flanges, the apertures being adapted to receive another of said shank portions, whereby said wall forms are detachably maintained on said brackets.

10. A mounting for wall forms comprising a base adapted to be secured to the ground; a first set of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; means to support a plurality of wall forms from said uprights; coupling members adapted to be secured to said uprights at selected vertical points; spreaders adapted to be supported by said coupling members; slides disposed on said spreaders and provided with bores; reinforcing ties passing through said bores and extending substantially parallel to said sets of uprights; and means for locking said reinforcing ties in said bores in predetermined horizontal positions.

11. A mounting for wall forms comprising a base adapted to be secured to the ground; a first set of seats forming supports; means to secure

said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; means to support a plurality of wall forms from said uprights; coupling members adapted to be secured to said uprights at selected vertical points; bores provided in said coupling members; spreaders passing through said bores; and means for locking said spreaders in said bores in selected horizontal positions.

12. A mounting for wall forms comprising a base adapted to be secured to the ground; a first set of seats forming supports; means to secure said supports at selected horizontal points to said base; track forming cross ties provided at ground level and secured with one end to said base at spaced points; means for securing the other end of said cross ties to the ground; a second set of seats forming supports adapted to slide on said cross ties; means to lock said second set of supports on said cross ties in selected horizontal positions; two sets of uprights supported in detachable manner one in each of said sets of seats; means to support a plurality of wall forms from said uprights; coupling members adapted to be secured to said uprights at selected vertical points; bores provided in said coupling members; spreaders passing through said bores; means for locking said spreaders in said bores in selected horizontal positions; a second set of coupling members slidably disposed on said spreaders; reinforcing ties slidably maintained in said second set of coupling members, said reinforcing ties being oriented at an angle to said spreaders; and means for locking said second set of coupling members and said reinforcing ties in selected horizontal positions.
